DESIGN FOR A CARPET.

SPECIFICATION forming part of Design No. 15,857, dated February 24, 1885.

Application filed January 14, 1885. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The face of the design is filled in with large 15 prominent leaf and flower figures, fern sprays, flag-like leaves, oak and maple and other leaves variously massed, all as clearly shown in the photograph.

I claim--

20 The design for a carpet, substantially as shown and described.

J. L. FOLSOM.
